DRY CLEANING OR WASHING APPARATUS

William Robertson MacDonald, Dundee, Scotland, assignor, by direct and mesne assignments, to James Wilson Nicol, Carnoustie, Scotland

Application February 25, 1935, Serial No. 8,185
In Great Britain April 3, 1934

2 Claims. (Cl. 68—18)

The present invention relates to cleaning and washing apparatus of the kind in which articles to be cleaned or washed, and more particularly articles of clothing, are subjected in a washing chamber to the action of a dry cleaning agent in the form of a liquid solvent, a movable basket being provided for agitating the articles to be cleaned.

It has been proposed to construct washing machines so that the axis of rotation of the basket does not coincide with the centre line thereof. Such an arrangement necessarily involves the provision of a relatively greater area of clearance between the basket and the inner surface of the washing chamber and consequently involves the use of a greater quantity of solvent. This is unimportant when the solvent is water but is a serious drawback if valuable solvents such as benzine are required to be used.

According to the present invention, the interior of the washing chamber, in the region occupied by the solvent, is provided with re-entrant projections situated in regions not swept by the basket, which latter is mounted so that the axis of rotation does not coincide with the centre line thereof.

When articles are placed in apparatus made according to the present invention they are not only flung backwards and forwards but also sideways in both directions, resulting in their being very thoroughly agitated and cleaned. Further the internal projections in the washing chamber enable a relatively small quantity of solvent to be satisfactorily used so that the apparatus can be economically operated.

The invention is illustrated in the annexed drawings, in which:—

Figure 1 is a detail side elevation of a machine constructed according to an embodiment of this invention.

Figure 2 is a sectional view taken on the line 2—2 of Figure 4.

Figure 3 is a top plan of the lower portion or half of the tub or housing.

Figure 4 is a detail side elevation of the stationary tub or housing with the oscillating means therefor removed from the frame structure.

Figure 5 is a top plan of the inner basket or clothes receiving member.

Figure 6 is a detail side elevation of the basket.

Figure 7 is a detail end elevation of the basket.

Referring to the drawings, and first to Figures 1 and 4, the numerals 12 and 13 designate a stationary tub or housing which is fixed in a frame F mounted on a base B. The stationary

tub comprises upper and lower sections 12 and 13 respectively, and the upper section 12 has a supply tank 11 positioned thereabove and connected thereto by means of a pipe 19 in which a valve 20 is interposed. A feed pipe 9 is connected at one end to the supply tank 11, and at the other end is connected to a dome 10 carried by a receiver 21 mounted on the base B.

The lower tub section 13 has a well 22 in the bottom thereof. The well is provided with an elongated drain 22a having an inclined bottom surface with an outlet opening 22b located at the lowermost part of the drain. A pipe 23 connects this outlet with the receiver 21. Preferably a filter 24 is interposed in this pipe 23 so that the cleaning liquid may be cleaned before entering the receiver 21, and the liquid entering the receiver 21 may be returned to the supply tank 11 by means of a pump (not shown) or other suitable means.

Disposed within the stationary tub or member 12—13 is a basket or perforate member 15, which is preferably rectangular in side elevation and provided with square ends 25 which are perforate as shown in Figs. 2 and 7. The basket 15 has alined trunnions or spindles 1 secured to each end 25, and, as shown in Fig. 5 these trunnions 1 are positioned one at one side of the longitudinal axis of the basket 15 while the other trunnion is positioned at the opposite side of the longitudinal axis of the basket 15. In Figure 6 it will be noted that the trunnions are also positioned one above the vertical center of the basket 15 and the other below the vertical center, so that when the material is placed within the basket 15 all of the articles will be thrown from side to side and from end to end of the basket 15.

A pinion 6 is secured to one of the trunnions or spindles 1, and this pinion 6 meshes with a toothed segment 5 carried by a rock shaft 26. The quadrant or toothed member 5 is oscillated from a power member 2 to which the quadrant 5 is connected as by a connecting rod 4, a crank 7 and a reduction gear 3. Preferably the connecting rod 4 is divided into two sections 4a and 4b which are mounted in a sleeve 27, and a spring 18 provides a yieldable connection between the abutting ends of the rod sections 4a and 4b.

In order to provide a means whereby the quantity of cleaning fluid in the well 22 may be reduced without affecting the liquid contact with the basket 15 and the articles within the basket, I have provided a plurality of projections 14

50

55

which are positioned along each side of the elongated drain 22a in the bottom of the well 22 and project upwardly in the direction of the path of the basket. These projections 14 will 5 displace the cleaning fluid, and as shown in Figure 2 the basket 15 will swing quite close to the projections, there being sufficient space between the projections 14 and the basket 15 so that the fluid in the well 22 will freely enter the basket. 10 This cleaning machine has been particularly de- signed for using a cleaning fluid which is quite expensive so that it is desirable that as small a quantity of fluid be used at a time as is absolutely necessary. Through the use of the pro- 15 jections 14 in the well 22 it will be apparent that only a small quantity of fluid will be dis- posed in the well 22, so that while this fluid may be used over and over again by passing the fluid through condensers and other dirt removing 20 means, still the quantity of fluid in the machine is only relatively small while at the same time the efficiency of the fluid is not impaired by using such a small quantity of fluid in physical contact with the material and clothes in the basket 15.

What is claimed is:

1. A cleaning means as set forth comprising a stationary casing, a well in the bottom of the casing, a rotary perforate member, means for rotatably mounting said rotary member upon an inclined axis in the stationary casing, said rotary member having flat walls, and means disposed in the well and positioned in regions out of the path of the rotary casing for reducing the liquid capacity of the well. 5
2. A cleaning means as set forth comprising a stationary housing, a well in the bottom of the housing, a substantially rectangular shaped perforate basket, means for rotatably mounting the basket in the housing on an axis inclined to the horizontal, and means in the bottom of the well and projecting upwardly therefrom in the direction of the path of rotation of the basket for displacing liquid in the well in regions outside the paths traced by the corners of said basket 15 20 while maintaining a predetermined liquid contact with the basket.

WILLIAM ROBERTSON MACDONALD.
